Primary Examiner — Mark Goodwin*(74) Attorney, Agent, or Firm* — Foley & Lardner LLP(57) **CLAIM**

We claim the ornamental design for a sealing gland, as shown and described.

DESCRIPTION

FIG. 1 is a top front perspective view of a sealing gland showing our new design;

FIG. 2 is a bottom, front perspective view thereof;

FIG. 3 is a top plan view thereof;

FIG. 4 is a bottom plan view thereof; and,

FIG. 5 is a front elevation sectional view thereof.

The ornamental design which is claimed is shown in solid lines in the drawings. The broken lines in the drawings form no part of the claimed design. Broken lines formed by equal length dashes show unclaimed subject matter. Broken lines formed by unequal length dashes (i.e., dash-dot) define bounds of the claimed design. Cross-hatching in sectional views indicates a sectioned portion unlimited by material; the cross-hatching itself is not part of the claimed design.
